Application July 3, 1944, Serial No. 543,255

7 Claims. (Cl. 171—97)

1

The present invention relates to vibrators, and, more particularly to vibratory interrupters of novel and improved character.

It is an object of the present invention to provide a vibratory interrupter of novel character in which a vibratory armature is simultaneously subjected to the joint effect of a constant and of an alternating magnetic field to produce vibrations thereof.

It is another object of the present invention to provide a novel vibratory interrupter organization in which an armature is mounted for vibration in a constant magnetic field and is alternately magnetized in opposite directions under the control of a system of contacts whereby the armature will be maintained in vibration.

It is a further object of the invention to provide a vibratory interrupter of the polarized type in which a constant magnetic field is set up by means of permanent magnets and an armature in said field is subjected to the effect of electromagnetic means alternately inducing magnetic poles of opposite polarity at the ends thereof to effect continuous vibratory motion of the armature.

It is also within the contemplation of the invention to provide a novel circuit organization for a polarized vibratory interrupter including a constant polarizing field, a vibratory armature and a driver coil whereby current will be alternately passed in opposite directions through the driver coil and the two halves of the primary winding of a transformer for maintaining the armature in vibration and to induce an alternating voltage in the secondary winding of said transformer.

Other and further objects and advantages of the invention will become apparent from the following description, taken in conjunction with the accompanying drawing, in which

Fig. 1 illustrates a side elevational view of a vibrator embodying the principles of the present invention and employing a pair of permanent magnets;

Fig. 2 depicts a preferred form of circuit organization of the vibrator illustrated in Fig. 1;

Fig. 3 shows a side elevational view of a modified embodiment of the invention likewise employing a pair of permanent magnets;

Fig. 4 is a circuit diagram of the vibrator shown in Fig. 3;

Fig. 5 illustrates another modified embodiment of the invention in side elevation employing electromagnetic means for producing a constant magnetic field;

2

Fig. 6 depicts the circuit diagram of the vibrator of Fig. 5;

Fig. 7 is a side elevational view of a further modification of the invention in which a pair of polarizing coils and a driver coil are employed; and

Fig. 8 is a similar view of another modified embodiment of the principles of the invention into a vibratory interrupter.

While a preferred embodiment of the invention is described herein, it is contemplated that considerable variation may be made in the method of procedure and the construction of parts without departing from the spirit of the invention. In the following description, and in the claims, parts will be identified by specific names, for convenience, but they are intended to be as generic in their application to similar parts as the art will permit.

20 Referring now more particularly to Fig. 1 of the drawing, reference characters 10 and 11 denote a pair of ferromagnetic frame plates, clamped at one end thereof and respectively carrying permanent magnets 12 and 13 at the other end thereof, setting up a constant magnetic field in gap 14 therebetween. Between plates 10 and 11 is held a driver coil 15, the winding space of which is defined by means of a ferromagnetic flange 16 and a non-magnetic or insulative flange 17 held together by means of a cylindrical sleeve 18, the ends of which are crimped around a corresponding opening in each flange. Flanges 16 and 17 are slightly larger in diameter than the distance between frame plates 10 and 11 and are provided with notches through which the said plates may extend and may securely hold the driver coil in its proper position. It will be also noted that ferromagnetic flange 16 constitutes a shortened magnetic path between the corresponding portions of the frame plates so that an efficient magnetic circuit is provided and a strong magnetic field of the indicated polarity is set up in air gap 14.

Progressing from frame plate 10, the stack 45 comprises an insulative spacer 19, a pair of side springs 20, insulative spacer 21, a pair of metal spacers 22 between which there is clamped one end of a reed or hinge plate 23, an insulative spacer 24, a pair of side springs 25, an insulative spacer 26, and frame plate 11. The stack is held together by means of stack screws 27 and nuts 28, said screws extending through aligned holes in the clamped elements. In accordance with usual practice, these holes are larger in diameter 50 than the stack screws to accommodate insulative

bushings (not shown) to insulate the several metallic elements from each other and from the frame plates.

The vibratory system is carried by hinge plate 23, to the free end of which there are secured 5 an armature plate 29, and reed arms 30 and 31 by means of rivets 32, there being a spacer plate 33 inserted between hinge plate 23 and reed arm 31. As it will be observed in Fig. 1, the riveted end of armature plate 29 is slightly offset with 10 respect to the other end thereof in order to obtain proper positioning of the armature in the magnetic field, the free end of the armature extending through the center hole of driver coil 15 into air gap 14. Reed arms 30 and 31 carry 15 vibratory interrupter contacts 34 and rectifier contacts 35. The vibratory interrupter contacts 34 cooperate with relatively fixed interrupter contacts 36 and 37, and the vibratory rectifier contacts 35 are cooperating with relatively fixed rectifier contacts 38 and 39, carried by side springs 20 and 25.

The circuit organization of the vibrator of the invention will be best understood from Fig. 2 in which similar reference characters have been used to denote corresponding parts. It will be noted that the ends of driver coil 15 are connected to fixed interrupter contacts 36 and 37, respectively, and also to the ends of primary winding 40 of 25 step-up transformer 41. A source of low voltage direct current 42 has its negative terminal grounded and connected to the vibratory system and its other terminal connected to the center tap of the primary winding. The ends of secondary winding 43 are respectively connected to fixed 30 rectifier contacts 38 and 39, and the rectified output voltage is developed between the center tap of said secondary winding and ground. A buffer condenser 44 is connected across the secondary winding and a filter condenser 45 and a resistor 46 are connected between the center tap of the secondary and ground in a manner well 35 understood.

From the foregoing description, the operation of the vibrator of the invention will be readily understood by those skilled in the art. It is to be observed at the outset that statically the permanent magnets 12 and 13 are set and of sufficient attractive force to bias the armature, causing one set of interrupter contacts, for example 34 and 36, to be closed.

At starting, current will flow from the positive terminal of the source, through lower half of primary winding 41, driver coil 15, closed contacts 34-36, and armature 29, back to the negative terminal of the source. At the same time current of considerably greater intensity will also start to flow from the positive terminal of the source, through the upper half of the primary winding, contacts 36-34, and armature 29, back to the other terminal of the source. Upon starting, this current will induce a current pulse of opposite direction in the other, lower, half of the primary and this pulse will be added to the current from the source flowing through the driver coil. This produces a flux in the armature of a polarity to repel the permanent magnet pole to which it was statically attracted and cause an attraction of the armature to the opposite permanent magnet pole 13. Consequently, the armature will move towards the attracting pole. As soon as the armature moves over, the other pair of interrupter contacts 34-37 are closed. This reverses the coil polarity, or the polarity of flux 40

induced in the armature, because current will flow from the positive terminal of the source through the upper half of the primary, driver coil 15, contacts 37-34, armature 29, and back to the negative terminal of the source. At the same time current of greater intensity will also flow from the positive terminal of the source, through the lower half of the primary, closed contacts 37-34, armature 29 and back to the negative terminal of the source, and the impulse induced in the other half of the primary will be added to the driver current, as before. The armature will be imparted such polarity as to be repelled by the pole 13 it is moving towards and to be attracted by the opposite pole, 12. During its travel towards 12, the armature will close contacts 34-36 and the cycle will begin anew.

Obviously, the driver coil will be alternately energized in opposite directions thereby maintaining the armature in continuous vibration so long as energy is supplied to the system. The primary winding of transformer 41 will be likewise alternately energized in opposite directions whereby a high alternating voltage will be induced in secondary winding 43. This alternating voltage is rectified by the conventional cooperation of the fixed rectifier contacts 38 and 39 with the corresponding vibratory contacts and the rectified high voltage may be withdrawn between the center tap of the secondary winding and ground. The driver coil inductance limits the coil current from changing instantaneously as the contacts close, so that the maximum "pull" or attraction occurs as the armature is moving 45 towards the attracting poles. This action then provides a balanced armature attracting force in each direction of armature motion, making possible symmetrical waveforms regardless of the exact type of contact mounting compliance mechanism used. It also makes possible high driving forces for the armature without increasing the coil energy required, as compared to conventional shunt, or driver coil type driving systems. Thus vibrators of the described characters have been successfully built and operated with a coil loss of only 0.2 watt at operating frequencies of about 400 cycles per second.

It is also to be observed that the magnetic circuit of the vibrator is very efficient and is formed with a minimum of air gaps. The magnetic circuit used is effective in providing the necessary magnetic bias to attract the armature and to close one set of interrupter contacts over the full range of interrupter contact spacing 55 changes normally encountered during the useful life of the unit. The principles of the invention are especially adaptable to the construction of high-frequency vibrators of very small dimensions. Thus, a practical unit of this type had an overall length of about one and one-half inches and a maximum diameter of about one inch and was successfully operated for long periods at about 400 cycles per second with good operational characteristics and low driving power.

In view of the polarized character of the unit, it is necessary to polarize the coil and the magnets with respect to the polarity of the source of current. In practical and commercial applications, it is desirable to bring out the coil connections to a plug having contact prongs so arranged that by rotating the vibrator by 180 degrees in its socket, the necessary connections for operation on either polarity of the battery with respect to chassis or ground will be obtained. Vibrator 60 mountings of this character are disclosed in U. S.

Patent 2,049,310 to Nulsen et al., dated July 28, 1936, to which hereby reference is made.

The modified embodiment of the invention illustrated in Fig. 3 and its circuit organization shown in Fig. 4 are in most respects similar to the one described in the foregoing and similar reference characters have been used to denote corresponding parts. Therefore, it will not be necessary to repeat the corresponding parts of the description. It will be sufficient to state that in this embodiment the constant magnetic field is provided by two horseshoe or U-shaped permanent magnets 52 and 53, respectively mounted in corresponding slots of ferromagnetic frame plates 50 and 51 by means of screws or rivets 54. Permanent magnets 52 and 53 are so arranged as to have their poles of opposite polarity facing each other, defining a pair of magnetic gaps 14 and 14a in which a strong magnetic field is set up. Driver coil 15 is provided on a spool constituted of two apertured flanges 16 and 17 and a sleeve 18 and is held between the two permanent magnets 52 and 53. Both flanges 16 and 17 are constituted of an insulating material, in contrast to the embodiment of Fig. 1, in which flange 16 is of a ferromagnetic character. Armature 29 extends through gap 14a and sleeve 18, into gap 14.

This modified embodiment has the advantage of greater magnetic efficiency, since in the attracted armature positions closed magnetic circuits are provided for both the driver coil and the permanent magnets and produce "pull" from each pair of poles, each side. Also, this arrangement provides the most efficient magnetic circuit and therefore the smallest size for any given deflecting forces on the armature. In view of the similarity of construction and of the circuit organization, the operation of this embodiment will be readily understood from that of the embodiment shown in Figs. 1 and 2.

The incorporation of permanent magnets into the vibrator structure, as shown in Figs. 1 to 4, introduces certain inconvenience and manufacturing difficulties. Thus, permanent magnets of the described character are relatively expensive and being generally constituted of magnetic alloys of very great hardness introduce problems into the manufacturing process. Moreover, vibrators of this type are permanently polarized and this has to be carefully considered when connecting them into a circuit. Although none of these problems is serious enough to interfere with the practical value of the described structures, in some cases it is advantageous to dispense with the permanent magnets and to employ electromagnetic means for setting up a constant polarizing field for the armature. A vibrator of this type is illustrated in Fig. 5.

This modified vibrator organization essentially comprises a pair of ferromagnetic frame plates 60 and 61 having one of their ends clamped in a stack and having their free ends extending away from the stack in parallel-spaced position. Between said plates is held a driver coil 62 having an axial hole 63 therein, through which armature 64 may extend. The polarizing field is produced by means of a polarizing coil 65 having a core 66 and a pair of L-shaped pole pieces 67 and 68 likewise held between the frame plate 60 and 61. The ends of pole pieces 67 and 68 extend towards each other and define a magnetic gap in which a strong magnetic field may be set up upon the polarizing coil being energized.

The stack comprises upper frame plate 60, insulative spacer 70, side spring 71, insulative

spacers 72, metal spacers 73 between which there is clamped one end of hinge plate 74, insulative spacers 75, side spring 76, insulative spacer 77, and lower frame plate 61. Clamping of the stack is effected in the conventional manner by means of stack screws 78 and nuts 79, said screws extending through aligned holes of the several elements.

The vibratory structure comprises two reed or contact arms 80 and 81 and the armature 64 secured to the free end of hinge plate 74, with the interposition of two spacer plates 82 and 83, by means of rivets 84. Vibratory contacts 85 and 86 are mounted at the ends of reed arms 80 and 81, respectively, and are adapted to cooperate with relatively fixed contacts 87 and 88, respectively mounted at the ends of side springs 71 and 76.

As it will appear from the circuit diagram of this vibrator shown in Fig. 6, polarizing coil 65 is directly connected across source of low voltage current 90. The driver coil 62 has its ends connected to stationary contacts 87 and 88 and also to the ends of primary winding 91 of transformer 92. Source 90 has its terminals connected to armature 64 and to the center tap of the primary winding. During operation of the structure, an alternating voltage is induced in secondary winding 93 and may be utilized directly, or after rectification.

The operation of this modified embodiment of the invention is substantially the same as that of the foregoing embodiments. It is to be observed at the outset that the contacts are adjusted for normal spacing so that when the polarizing coil 65 is not energized, both interrupter contacts are open (Fig. 5). On starting, polarizing coil 65 is energized and the system will be biased so as to close one set of contacts, for example, 85 and 87 (Fig. 6). Current of such direction will now be passed through driver coil 62 as to induce a magnetic polarity in the armature causing deflection thereof in the contact-breaking direction until the other set of contacts, 86 and 88, will be closed, reversing the direction of current flow through the driver coil, etc. Clearly, the armature will be maintained in continuous vibration and current will be passed in alternate directions through the two halves of the primary winding, inducing alternating voltage in the secondary winding, which may be rectified, if desired, by means of a rectifier tube, or by means of a set of synchronous rectifier contacts operated by the armature.

It will be noted that this modified embodiment is dynamically the equivalent of the structure of Fig. 1, the permanent magnets being replaced by an electromagnet. While the polarizing coil represents an additional load on the source, this load may be held within low limits and does not substantially affect the overall efficiency of the vibrator. The advantage of this embodiment is that it is normally non-polarized, that is for an interrupter unit properly connected, it will operate from either battery polarity without reversing the coil connections. It also has the same type of impact starting as is obtained with a shunt type vibrator.

The most advantageous magnetic system in a vibrator of this type is obtained by means of two polarizing coils, as this is illustrated by way of example in Fig. 7. This vibrator comprises a pair of frame plates 100 and 101 clamped in a stack at one end thereof and carrying a pair of U-shaped ferromagnetic members, 102 and 103, at the other end thereof. The ends of members 102 and 103 are extending towards each other and

define a pair of air gaps 104 and 105. A driver coil 106 is mounted between members 102 and 103 and has an axial hole 107 therein substantially in alignment with gaps 104 and 105. Polarizing coils 108 and 109 are mounted around one extension of members 102 and 103, said coils being connected in parallel or in series with each other and are directly energized from the source so as to set up poles of opposite magnetic polarity in both air gaps.

The stack comprises frame plate 100, two insulative spacers 110, side spring 111, insulative spacers 112, metal spacers 113 between which there is clamped one end of hinge plate 114, insulative spacers 115, side spring 116, insulative spacers 117, and lower frame plate 101. The stack is held together in the conventional manner by means of stack screws 118 and nuts 119.

The vibratory system includes a pair of reed arms 120 and 121, carrying vibratory contacts 122 and 123, respectively, at the ends thereof. These reed arms are riveted with the interposition of suitable spacers to the ends of hinge plate 114 and armature plate 124. Vibratory contacts 122 and 123 respectively cooperate with relatively fixed contacts 125 and 126 mounted at the ends of spring arms 111 and 116. Armature 124 extends through air gap 105 and driver coil 107 into air gap 104.

This vibrator is to a substantial extent similar to the one shown in Fig. 3 with the difference that the two permanent magnets 52 and 53 of the previous embodiment are replaced by U-shaped ferromagnetic members 102 and 103 and polarizing coils 108 and 109. Therefore, the operation of this modified embodiment of the invention should be obvious to those skilled in the art.

A further vibrator organization whereby symmetrical armature actuating forces may be obtained in each half-cycle is depicted in Fig. 8. This vibrator includes a generally U-shaped ferromagnetic frame 120 having a stack clamped between its legs and a driver coil 121 mounted in its bight by means of an iron core 122 ending in a pole piece 123. The stack comprises the upper portion of frame 120, insulative spacer 124, side spring 125, insulative spacers 126, hinge plate 127, insulative spacers 128, side spring 129, insulative spacer 130, and the lower portion of frame 120. The stack is held together by means of conventional stack screws 131 and nuts 132.

The vibratory system includes a pair of reed arms 133 and 134 carrying vibratory contacts 135 and 136, respectively, at the ends thereof, and armature plate 137, the reed arms and the armature being secured to the free end of hinge plate 127 by means of rivets 138. Vibratory contacts 135 and 136 respectively cooperate with relatively fixed contacts 139 and 140 mounted on side springs 125 and 129. Two small permanent magnets 141 and 142 are mounted on frame 120 so as to have their poles of opposite polarity defining a magnetic gap through which the armature extends in proximity to pole piece 123 of driver coil 121. As in the previous embodiments of the invention, the driver coil is connected across the primary winding of the transformer to which the stationary contacts are likewise connected. The permanent magnets bias one set of interrupter contacts, for example 135-139, closed statically over the normal contact spacing range encountered, so as to obtain the desired starting conditions. During the operation of the vibrator, driver coil 121 is alternately energized in opposite directions and will induce magnetic poles in the

terminal region of the armature in accordance with the direction of the driver current so that vibratory movement of the armature will follow in the same way as in the previous embodiments.

This arrangement has the advantage of allowing a more conventional form of structure although it has a somewhat greater overall length than the arrangements disclosed in the foregoing.

Although the present invention has been disclosed in connection with a few preferred embodiments thereof, variations and modifications may be resorted to by those skilled in the art without departing from the principles of the present invention. In accordance with these principles an alternating current sets up an alternating flux in an armature which is operating in a constant magnetic field so that during each half-cycle the armature is repelled from the pole it is moving from and is attracted by the pole it is moving towards, thus providing symmetrical armature driving force in each direction of armature travel. All of these variations and modifications are considered to be within the true spirit and scope of the present invention as disclosed in the foregoing description and defined by the appended claims.

What is claimed is:

1. A vibratory interrupter comprising in combination means including a pair of permanent magnets facing each other in cooperative magnetic relationship for establishing a constant magnetic field in a pair of aligned gaps, a ferromagnetic member mounted for vibration extending through said gaps, electromagnetic means selectively coupled to a source of current and adapted when energized to magnetize said member and to cause deflection thereof in said field, and a system of contacts operable by deflection of said member alternately to energize said electromagnetic means in opposite directions thereby to maintain said member in vibration.

2. A vibratory interrupter comprising in combination means including a pair of permanent magnets having their poles spacedly facing each other to define a pair of aligned gaps with oppositely directed constant magnetic fields, a ferromagnetic vibratory member extending through the first and into the other of said gaps, windings of wire spacedly surrounding the portion of said member between said gaps and adapted when energized to magnetize said member and to cause deflection thereof in said magnetic fields, and contact means selectively coupled to a source of current and operable by deflection of said member to alternately pass current through said windings in opposite directions thereby to produce vibrations of said member.

3. A vibratory interrupter comprising in combination a stack, a pair of frame plates spacedly clamped in said stack, a substantially U-shaped permanent magnet mounted at the end of each of said plates to have their poles of opposite polarity facing each other defining a pair of aligned magnetic gaps, a hinge plate clamped in said stack at one end thereof and bearing an elongated ferromagnetic armature at the other end thereof extending through one of said gaps into the other, a driver coil surrounding the portion of said armature between said gaps and having an axial opening through which the armature may extend, a set of vibratory contacts on said armature selectively coupled to a source of current, and stack-clamped relatively fixed interrupter and rectifier contacts cooperating with 75 said vibratory contacts adapted to control a low-

voltage input and a high-voltage output circuit and to alternately energize said coil in opposite directions thereby to maintain the armature in vibration.

4. A vibratory interrupter comprising in combination a stack, a pair of frame plates clamped in said stack in parallel-spaced position, a pair of U-shaped permanent magnets mounted between said plates to have poles of opposite polarity facing each other defining a pair of magnetic gaps, a driver coil held between said magnets and having an axial opening therein aligned with said gaps, a ferromagnetic armature mounted for vibration in said stack and extending through said gaps and through the opening in said coil, a set of vibratory contacts on said armature, stationary interrupter and rectifier contacts cooperating with said vibratory contacts, one of said interrupter contacts being normally closed, stack-clamped springs for supporting said stationary contacts, connections between said coil, said interrupter contacts, a source of current and the primary winding of a transformer to alternately pass current of opposite direction through said coil and winding, and connections between the secondary winding of said transformer and the said rectifier contacts to rectify the alternating voltage induced in the said secondary winding.

5. A vibratory interrupter comprising, in combination, means including a pair of permanent magnets facing each other in additive magnetic relationship for defining a pair of aligned gaps and establishing a constant magnetic field therein, a vibratory reed having a paramagnetic portion extending through said gaps, a driver coil selectively coupled to a source of current and adapted to magnetize said paramagnetic portion to cause deflection thereof in said field, and a system of contacts on said reed operable by deflection of said paramagnetic portion to alternately energize said driver coil with currents of opposite polarities thereby to maintain said reed in vibration.

6. A vibratory interrupter comprising, in combination, means including a pair of permanent magnets facing each other in additive magnetic relationship for defining a pair of aligned gaps

and establishing a constant magnetic field therein, a vibratory reed having a paramagnetic portion extending through said gaps, a driver coil selectively coupled to a source of current and mounted between said gaps and having an axial passage therein for receiving said paramagnetic portion, whereby energization of the driver coil causes deflection of the paramagnetic portion in said field, and a system of contacts on said reed operable by deflection of said paramagnetic portion to alternately energize said driver coil with currents of opposite polarities thereby to maintain said reed in vibration.

7. A vibratory interrupter comprising in combination a stack, a pair of frame plates clamped in said stack in parallel-spaced position, a pair of permanent magnets mounted between said plates to have poles of opposite polarity facing each other defining a pair of magnetic gaps, a driver coil held between said magnets and having an axial opening therein aligned with said gaps, a ferromagnetic armature mounted for vibration in said stack and extending through said gaps and through the opening in said coil, a set of vibratory contacts on said armature, stationary interrupter contacts cooperating with said vibratory contacts, one of said interrupter contacts being normally closed, stack clamped springs for supporting said stationary contacts, and connections between said coil, a source of current and the primary winding of a transformer to alternately pass current of opposite direction through said coil and winding.
